UNITED STATES PATENT OFFICE.

WILLIAM S. WEIR, OF MONMOUTH, ILLINOIS.

CULTIVATOR.

SPECIFICATION forming part of Letters Patent No. 320,519, dated June 23, 1885.

Application filed August 6, 1883. (No model.)

To all whom it may concern:

Be it known that I, WILLIAM S. WEIR, residing at Monmouth, in the county of Warren and State of Illinois, and a citizen of the United States, have invented certain new and useful Improvements in Cultivators, of which the following is a full description, reference being had to the accompanying drawings, in which—

Figure 1 is a top or plan view; Fig. 2, a cross-section on line *x x* of Fig. 1; Fig. 3, a cross-section on line *y y* of Fig. 1; Fig. 4, a vertical section of the coupling on line *z z* of Fig. 1.

The object of this invention is to provide a simple and efficient means for holding the connecting-bow of a tongueless cultivator in a substantially vertical position without adding to the cost of the cultivator and without complicating the structure; and its nature consists in holding the bow up by means of the coupling, and in the several parts and combinations of parts hereinafter set forth and claimed as new.

In the drawings, A A' indicate the drag-bars forming the cultivator-beam; B, the bow; C, the coupling; *a*, the spindle; *a'*, connecting-plate; *b*, upper and lower coupling-plates; *c*, coupling-bolt; *d*, circular projections on the inner sides of the coupling-plates; *e*, upper part of the coupling-box; *f*, adjusting-holes; *g*, supporting ears or projections; *h*, lower half of the journal-box.

The drag-bars A A' are formed by bending a metal bar of suitable dimensions around the coupling-pin *c* so as to form bars of unequal length, as shown, the outer ones, A', being the longest. These drag-bars are provided with suitable cultivator-shovels and guiding-handles, as shown, or in any well-known manner.

The bow or coupling arch B is also made of metal of suitable dimensions, and its ends are turned out horizontally and form either spindles *a* for attaching wheels, or plates *a'* for attaching runners, as either wheels or runners may be used. The horizontal portion is rounded to receive the coupling C.

The coupling C is made of plates *b*, which are alike, and which are attached to the upper and under sides of the beams A A'. The rear ends of these plates are furnished with projections *b'*, which fit between the bars A A', and they are also furnished with circular projections *d*, which fit into the boxes *e h*, and

form the pivot by which the beams have lateral movements. These two plates are held together by a single bolt, *c*, which passes through them in contact with the bend of the bars forming the cultivator-beam. The lower box, *h*, is a small one and moves with the under plate *b* whenever the space between the beams is adjusted. The upper half-box, *e*, does not move with the coupling when it is adjusted, but is provided with holes *f*, by means of which the adjustment of the space between them is effected. The half-box *e* is forked at its inner end, forming the prongs *g*, which stand one on each side of the bow or arch B, and as they are above the horizontal portion of the bow or axle they prevent the bow from falling down, as they hold or support it whenever it falls against the projection or ears *g* in either direction. This makes a simple and efficient support for the bow without adding to the number of parts forming the cultivator-coupling, and holding it in a substantially vertical position without any connection of the parts used for attaching the team.

The construction shown is the simplest and best form known to me; but it is evident that the box *e* may be made of a separate plate and be placed on top of the coupling, so as to give it a higher position and the bow or axle less leverage upon or against the ears; or the inner end of the box may be turned up so as to bring the projections or ears *g* into a higher position, and such other modifications as will readily suggest themselves to any good mechanician may be used.

I have shown the bow in the form of a continuous axle and without any separate device for attaching the team. Drag-bars may be directly attached to the coupling C, or such devices as are shown in my Patent No. 274,070, March 13, 1883, may be applied, this part of the cultivator being left to be of such construction, as may be desired.

It is also evident that the bow, instead of being in the axle form shown, when other suitable devices are applied, may be jointed between the bow and the coupling, and the bow still be held in a vertical position by the same means; and I do not limit myself to the application of the half-box or forked plate to cultivator-beams having the construction shown, nor to the specific form of coupling described,

as it may be applied to many of the couplings for cultivator-beams now in use.

What I claim as new, and desire to secure by Letters Patent, is as follows:

- 5 1. The combination, with the arch or bow B and the drag-bar or beam-coupling C, of the ears *g g*, projecting laterally from and forming a rigid part of the coupling, and extending on opposite sides of the arch or bow above its
- 10 wheel axle or spindle for preventing the arch or bow from falling down, substantially as described.

2. The box or bar *e*, having the ears *g* and adjusting-holes *f*, and half-box *h*, in combination with the plates *b*, having the projections *e*, substantially as and for the purpose specified. 15

WILLIAM S. WEIR.
